(57) **CLAIM**

The ornamental design for a package for absorbent articles, as shown and described.

DESCRIPTION

FIG. 1 is a perspective view of a new design for a package for absorbent articles;

FIG. 2 is a front plan view thereof;

FIG. 3 is a back plan view thereof;

FIG. 4 is a left side view thereof;

FIG. 5 is a right side view thereof;

FIG. 6 is a bottom view thereof; and,

FIG. 7 is a top view thereof.

In the drawings the broken lines are for the purpose of illustrating portions of the package for absorbent articles that form no part of the claimed design.
